CLAIM

The ornamental design for a storage bag, as shown and described.

DESCRIPTION

FIG. 1 is a front view of a storage bag showing our new design;

FIG. 2 is a rear view thereof;

FIG. 3 is a left side view thereof;

FIG. 4 is a right side view thereof;

FIG. 5 is a top view thereof; and

FIG. 6 is a bottom view thereof.

FIG. 7 is a front view of an alternate embodiment of a storage bag showing our new design;

FIG. 8 is a rear view thereof;

FIG. 9 is a left side view thereof;

FIG. 10 is a right side view thereof;

FIG. 11 is a top view thereof; and,

FIG. 12 is a bottom view thereof.

The shade lines in the Figures show transparency or translucency.

The Figures are shaded with light and dark gray shading to show contrasting appearances, including color. The front flap of the storage bag is shaded to show one appearance and the rear flap is shaded to show a different appearance.
